UNITED STATES PATENT OFFICE.

CHAUNCEY W. MILLS, OF ROCHESTER, NEW YORK.

PACKING FOR PISTON-RODS.

SPECIFICATION forming part of Letters Patent No. 387,900, dated August 14, 1888.

Application filed March 24, 1888. Serial No. 208,407. (No model.)

To all whom it may concern:

Be it known that I, CHAUNCEY W. MILLS, of Rochester, in the county of Monroe and State of New York, have invented certain new and useful Improvements in Packing for Piston-Rods; and I do hereby declare that the following is a full, clear, and exact description thereof, reference being had to the accompanying drawings, and to the letters of reference marked thereon, which form part of this specification, in which—

Figure 1 is a detail longitudinal sectional view through a cylinder-head stuffing-box, showing my improved piston-rod-packing devices applied. Fig. 2 is a face view of the expanding head. Fig. 3 is a side view of the sleeve and head.

The present invention is an improvement in piston-rod packings; and its objects are to provide means whereby the packing will be automatically compressed around the piston-rod to form a steam-tight dam when steam is admitted into the cylinder on the side adjoining the stuffing-box.

Further objects of the invention are to automatically compensate for wear of the packing and to improve the bearings of the piston-rod in the stuffing-box, all of which I accomplish by the means hereinafter described, illustrated in the drawings, and particularly specified in the claims hereto appended.

Referring to the drawings by letter, A designates an ordinary cylinder-head; B, the stuffing-box; C, the piston-rod, and D the annular gland-plate surrounding rod C and suitably secured to the face of box B.

E is a sleeve surrounding rod C and extending into the cylinder, so as to form the bearing for rod C through the cylinder-head.

F is a head on the front end of sleeve E, about equal in diameter to the interior diameter of box B. This head is conically recessed in its front face, the sides of the cone converging toward sleeve E and ending at an annular shoulder, e, at the front of the sleeve, as shown. The annular wall of head F is radially slotted, as shown at f, or in other suitable manner, so that head F resembles somewhat a crown-wheel, and the object of these slots is herein-after stated.

On the sleeve E is placed a coiled spring, G, which bears against the face of head A and the

head F, as shown, the spring serving to force the head and sleeve forward on rod C.

H is a ring-bushing interposed between rod C and gland D. This ring H is provided with an annular collar, h, by which its introduction into box B is limited, and the inner face of said ring is concaved, as shown, opposite the conical head F. Any suitable packing, I, is placed in the space between head F and ring H, so as to completely fill the conical recess in head F, but not the slots f therein. When steam is admitted into the cylinder on the side next box B, pressure is had on sleeve E to force the same and head F forward, compressing packing I longitudinally, and steam, leaking between sleeve E and rod C or between the sleeve and head A enters the slots f in head F and distends the intermediate portions or teeth of the head, causing it to bind tightly in box B, and at the same time the steam exerts an annular compression on packing I below the slots f, causing the same to make a complete steam-tight joint and preventing any leakage of the steam through the stuffing-box, even though the rod C were worn or channeled in its periphery. The head by its expansion will thus tighten the packing in box B, while the active steam-pressure is on the same end of the cylinder. When this pressure is released during the return-stroke of the piston, the compressing of the packing I on the rod C is of course diminished, and consequently the wear on rod and packing is lessened nearly one-half. The packing I is first compressed by means of the plate D, ring H, and spring G, and the spring will cause head F to automatically follow up the packing I to compensate for its wear, so that the packing requires but little attention, and, owing to the steam getting outside the packing through slots f, the latter is kept soft and in working condition, whereas in ordinary packings the exterior of the packing hardens and must be picked out and renewed. In the present case when the packing becomes worn down a new ring of packing may be inserted without removing the old, which can be entirely used.

It will be seen that sleeve E forms a bearing for rod C, extending from the interior of the cylinder partly through the stuffing-box, and by it all contact of the rod with the cylinder

head is prevented, so that there is no wear on the head, and when sleeve E becomes worn it can be readily replaced and thus preserve tight joints between the piston-rod and cylinder-head.

Having described my invention, I claim—

1. The combination of the piston-rod, stuffing-box, and gland-bushing with the sleeve on said rod, the head F, conically recessed on its front face and radially slotted through the walls of such recessed portion, to permit the expanding thereof, and the interposed packing between said head and bushing, all constructed and arranged substantially in the manner and for the purpose described.

2. In a piston-rod packing, the combination of the gland-bushing, stuffing box, and piston-rod, with the spring-controlled, conically-recessed, and slotted head F, the sleeve E, ex-

tending into the cylinder, and packing I, all 20 constructed and arranged substantially in the manner and for the purpose specified.

3. The combination of head A, box B, rod C, and the gland-bushing, substantially as described, with the sleeve E, projecting into the 25 cylinder, the slotted expansive head F, conically recessed in its front face and united to said sleeve, the spring G, and packing I, all constructed and arranged to operate substantially in the manner and for the purpose de- 30 scribed.

In testimony that I claim the foregoing as my own I affix my signature in presence of two witnesses.

CHAUNCEY W. MILLS.
